UNITED STATES PATENT OFFICE.

THOMAS JOHN ARTHUR SHEPHERD, OF WAITAANGA, NEW ZEALAND.

WIRE-ROPE-SPlicing TOOL.

Application filed March 9, 1928, Serial No. 260,461, and in New Zealand January 18, 1928.

This invention has been devised with the object of providing an improved tool for use in the operations of wire rope splicing, as for instance splicing two ends together by the well known inlaying system, and the formation of eye splices upon a rope end. The tool is intended to replace the ordinary marlin spike generally used in the performance of these operations and by its employment greatly facilitates and expedites the carrying out thereof. In effect, the tool is a development of the ordinary marlin spike.

The invention consists in the construction of a marlin spike bar with features of novel nature that provide for the rope strands in inlaying work being quickly and accurately inlaid, and in the combination with the bar of means whereby the rope strands in eye splicing operations may be gripped for tightening and loosened and rolled, as is required in these operations.

The tool is illustrated in the accompanying drawings, in which:—

Figure 1 is a plan, and

Figure 2 a side elevation thereof.

Figure 3 is a longitudinal side sectional elevation.

Figure 4 is a cross section on the line 4—4 of Figure 1.

Figure 5 is a cross section on the line 5—5 of Figure 1.

Figure 6 is an enlarged sectional elevation of a portion of the tool.

According hereto the tool is formed by a metal bar 10 of ordinary marlin spike type, that is, with a point 11 at one end, and a cross handle 12 at the other, but in this invention, the bar is made of approximately elliptical form in cross-section so that when the strands of a rope are pierced by the point 11, they may be opened out by turning the bar to cause its major axis to extend across the rope and thereby facilitate the insertion of the jointing strand in ordinary inlay splicing operations. Such pointed end 11 also is formed with an eye 13 extending through it at an angle in the longitudinal line of the tool. This is for the purpose of threading through the point, the strand of rope to be inlaid, so that then, by winding the tool round and round along on the convolutions of the rope, such strand will be inlaid with the rope strands in the required manner. The point, in addition, is formed with notches 13^a in its surface disposed, one on each side of its major diameter, and in

line with the said eye 13 so that the rope strands will fit into such notches and keep the tool point in place while it is being wound upon the rope. Also the surface of 60 the point may be grooved with a groove 14 leading to the eye, to aid the laying of the rope strand through the eye.

The said bar 10 also, in this invention, has combined with it, means whereby a strand threaded through the said eye 13 may be gripped and held, and then released to move through the eye, and a fresh grip obtained at another point, in continuous operations, as is required when splicing a 70 strand in eye splicing operations.

These means comprise a lever 15 that is laid within a groove 16 to extend along the main bar 10 and to project at its back end. The said lever is pivoted at 17 in the bar 75 near its forward end and such forward end passes through a slot opening 18 in the bar and underlies the eye 13 in the bar point. The lever 15 is adapted to turn on its pivot 17 so that by raising and lowering the back 80 end, the forward end is made to move away from and towards the side of the point 11 into which it is designed to fit, the lever being so fitted into the bar that when turned in, the whole of its forward part lies within 85 the cross-sectional area, allowing of the bar being used in its usual functional operations.

The forward end of the lever 15 is itself formed with an eye 19 that when such end 90 is turned up, makes coincidence with the eye 13 in the point, so as to form one therewith. In the inlay splicing operations beforementioned the strand is threaded through both these eyes 13 and 19, which form one, and 95 in the eye splicing operations the strand may also be threaded through both and the lever 15 worked in and out to slide its end on such strand.

Fitted lengthwise to slide in the lever top 100 is a metal strip 20, the back end of which is connected to a rocking operating lever 21 that is pivoted to the main lever end, and is so designed as by an in and out movement, to push the strip 20 inward and to draw it 105 outward, along within the lever. The said rocking lever 21 is pivoted in bearings 22 upon the end of the lever 15 and extends upwardly. The rear end of the strip 20 passes through this lever 21 and has a stop 110 23 upon its extremity so that the desired movements of the strip are obtained through

the rocking of the lever. The forward end of this strip 20 extends to the rear edge of the eye 19 in the lever, and is rounded so that when the strip is drawn back, it conforms with the eye, as shown by the full lines in Figure 6, allowing a rope strand to pass freely through it. When the strip is pushed in as in dotted lines in Figure 6, it extends into the eye area and provides for such strand being jamped and gripped between it and the other side of the eye, with a grip that will hold it tightly while the strand is being twisted on the main part of the rope. Then by alternately gripping and releasing the strand, synchronously with working the lever end in and out, as shown by the dotted lines in Figures 3 and 6, the strand may be gripped and wound in the manner necessary in effecting these operations.

20 I claim:—

1. A wire rope splicing tool comprising the combination with a pointed bar having an eye formed to extend through it near its pointed end, and formed with a slot 25 extending longitudinally therein, of a lever pivoted in such slot so that it extends longitudinally with the bar to cause its forward end to lie beneath the said eye, on one side of the pointed end of the bar, and the rear 30 end to lie along the bar upon its other side, and which lever at such forward end is formed with an eye that is adapted to coincide with the eye in the bar point when the forward end is turned inward upon the bar 35 length, substantially as specified.

2. In a wire rope splicing tool constructed in accordance with claim 1, the combination with the said lever, of a strip laid along the outside thereof and made movable longitudinally thereon, such strip having its forward end arranged to extend into the eye 40 of the lever and its rear end to project be-

yond the rear end of the lever, and means upon the lever end whereby the strip may be moved to and fro upon the lever, substantially as specified. 45

3. In a wire rope splicing tool as claimed in claim 1, the combination with the lever, of a strip arranged along the outside thereof and movable longitudinally thereon, said 50 strip having its forward end arranged to extend into the eye of the lever and its rear end to project beyond the rear end of the lever, and another lever rockably mounted upon the rear end of the first mentioned 55 lever and projecting upwardly and through which the rear end of the said strip is loosely passed and held.

4. In a wire rope splicing tool as claimed in claim 1, wherein the bar is of elliptical 60 shape in cross section and is formed with notches on opposite sides of its pointed end and in line with the eye therein, and the slot being shaped to accommodate the lever within the pointed end and throughout a 65 portion of the length of the bar adjacent the pointed end, substantially as and for the purposes set forth.

5. A wire rope splicing tool comprising in combination, a bar with a pointed end provided with an eye and also provided with a diagonal slot extending forward and intersecting the eye and with a groove extending longitudinally rearwardly and communicating with the slot, and a lever having an eye 70 adjacent one end and pivoted to the bar and within the slot so that the eye aligns with the eye in the pointed end of the bar while the opposite portion lies within the groove on the opposite side of the bar, substantially as and for the purposes set forth. 75
In testimony whereof, I affix my signature.

THOMAS JOHN ARTHUR SHEPHERD.
